UNITED STATES PATENT OFFICE.

ALFRED G. HOLCOMBE, OF NEW YORK, N. Y., ASSIGNOR TO THE EQUITABLE ELECTRIC COMPANY, OF SAME PLACE.

ELECTRICAL COMMUNICATING SYSTEM FOR HOTELS.

SPECIFICATION forming part of Letters Patent No. 336,809, dated February 23, 1886.

Application filed August 15, 1885. Serial No. 174,462. (No model.)

To all whom it may concern:

Be it known that I, ALFRED G. HOLCOMBE, a citizen of the United States, residing at New York, county and State of New York, have invented certain new and useful Improvements 5 in Electrical Communicating Systems for Hotels, of which the following is a specification.

This invention has for its object to facilitate the service of hotels, &c., by providing 10 each room or apartment with a call and communicating apparatus placed in electrical connection with an ordinary annunciator, and a message-indicator located at the office or a central point, whereby the occupants of the 15 rooms or apartments may make known their wants directly at the office without having to wait for the attendance of an employé to receive their messages, as under the call systems now in vogue. In devising an electrical system 20 adapted to perform these functions simplicity in the construction of the instruments and in the arrangement of the connecting-lines has been kept in view, and also the non-interference between the various communicators, 25 should two or more be called into requisition at the same time. The communicators are each provided with a pointer adapted to be 30 set opposite any one of a number of calls or messages marked thereon, and they are all in connection with the message-indicator by means of separate lines, including their respective corresponding number-actuating device of the annunciator, and one main line from the battery is connected to all of the 35 communicators. The circuit-lines used by me are similar to those of an ordinary annunciator system, my communicators being substituted for the push buttons or circuit-closing devices located in the various rooms; and the message-indicator at the office is included in the 40 individual circuits between the annunciator and the call-bell, said call-bell circuit taking in a part of the battery to the main line, and another line from the indicator, which includes 45 its electro-magnetic-actuating devices, takes in the whole of the battery to the main line. The part of the battery in the call-bell circuit supplies only sufficient current to actuate the call-bell and the annunciator when any of the

communicators are set, and the whole battery 50 supplies sufficient current to actuate both the electro-magnetic devices of a communicator and the indicator when the attendant at the office is receiving a message.

Figure 1, Sheet 1, of the accompanying drawings illustrates, generally, my electrical communicating system. Fig. 2, Sheet 2, is a view of one of the communicators with its front plate and pointer removed. Fig. 3, Sheet 2, is a central section of the same. Fig. 4, Sheet 60 2, is a view of the indicator with the front plate and pointer removed; and Fig. 5, Sheet 2, is a section view of the same on the line xx .

Referring to Fig. 1, $a a' a^2$, &c., are the communicators, with a number of calls or messages 65 printed or marked on the front plates, or marked on tablets attached thereto, according to the requirements of the case, some blank spaces being shown, to be filled up with special messages, as desired.

b represents an annunciator of ordinary construction connected by the lines $c c' c^2$, &c., to the several communicators $a a' a^2$, &c., and to independent contact-springs in the message-indicator d by the lines $e e' e^2$, &c. A toothed 75 plate in this indicator, adapted to make and break contact with all the springs joined to the lines $e e' e^2$, &c., is connected through its operating handle d' and spring by the wire f to the part g of the battery, and in this wire 80 f is included the call-bell f' . The front plate of the indicator d , to which the push-buttons $d^1 d^2$ are electrically connected, is joined to the end of the other part, g' , of the battery by the wire g^2 , which includes the electro-magnetic device contained in the indicator, to be 85 hereinafter explained. The other end of the part g of the battery is, by means of the main line h , connected to an electro-magnetic device contained in each of the communicators 90 $a a' a^2$, &c.

The operation of the system, omitting details of construction, to be hereinafter described, is as follows: All of the circuits are open when the communicators are in their normal condition—that is, with the indexes or pointers at zero or against the fixed stops, as indicated in all of them. The occupant of any

room or apartment requiring to be served sets the pointer of his communicator opposite the message indicative of his want—as, for instance, occupant of room 2 sets his communicator at "District Messenger." The pointer in being so set closes the circuit of this communicator with the part *g* of the battery, the current from which passes through the annunciator *b*, thereby exposing the corresponding number 2, through the indicator *d*, and by the wire *f*, through the call-bell *f'*, back to battery *g*. This current, while sufficient to actuate the call-bell, does not set in action the electro-magnetic device in the communicator, and said call-bell continues to ring as the pointer remains in the position in which it is set until the clerk or attendant at the office presses the handle *d'* of the indicator down. By this action the toothed plate of the indicator is moved and all the individual circuits are broken in the indicator, and the call-bell circuit is also broken. The attendant now pushes in the button *d''*, bearing the number indicated by the annunciator—viz., button 2— and this connects the spring attached to the wire *e'* with the electro-magnetic device in the indicator *d*, and completes the circuit by the wire *g''* through the whole of the battery *g'* and *g*, the current of which, flowing through the circuit, actuates the electro-magnetic devices in the communicator and indicator, thereby releasing the pointer of the communicator, which is, by means of a spring-motor, caused to move back to zero, or to the fixed stop, and in doing so makes and breaks the circuit a certain number of times, according to the position of the selected message on the dial. Now, this intermittent action of the battery-current actuates the electro-magnetic device in the indicator *d*, each pulsation causing its pointer to move consecutively opposite the messages marked on its dial, which are arranged in a manner similar to the markings on the dials of the communicators *a*, *a'* &c., so for the case in consideration, "District Messenger" being the fourth message on the dials, four breaks in the circuit will occur as the pointer of the communicator *a'* moves from "District Messenger" back to zero, and the pointer of the indicator *d* will move forward four divisions and stop opposite "District Messenger," thus notifying the attendant that a district messenger is wanted by occupant of room No. 2. Upon the button No. 2 and the handle *d'* of the indicator being released, the mechanism of the indicator assumes normal position, with its pointer brought back by means of a spring-motor to the zero-point. Now, should any of the communicators in the other rooms be set while the attendant is receiving a message from one of the rooms, as just described, this setting of the other communicators will in no wise interfere with the operation of receiving said message, because all of the individual circuit lines are broken at the springs attached to the lines *e* *e'*, &c., by the movement im-

parted to the toothed plate by its handle *d'* of the indicator, and the only closed circuit is the one whose number is exposed at the annunciator and the corresponding button, *d''*, of the indicator manipulated by the attendant; but as soon as he releases the handle *d'* and button *d''*, after the message is indicated by the indicator, then the call-bell *f'* will again ring and the annunciator give notice of the room or rooms wishing service, the attendant then receiving the messages in order, as before described.

The improvements in electrical apparatus, by means of which my improved method of communication is carried out in an efficient and simple manner, are clearly shown on Sheet 2 of the drawings, Figs. 2 and 3 showing on an enlarged scale the mechanism of one of the communicators *a*, contained in a circular case, *i*, on the front plate, *i'*, of which the messages are marked or attached. The pointer *i''*, provided with a handle, is secured to the end of a shaft having bearings in the center of the case *i* and to this shaft is attached the coil-spring *i'*, whose other end is fastened to the case *i*, in such a manner as to be wound up when the pointer *i''* is moved forward, and by its resilience moves the pointer back to zero when released. On the shaft is secured the toothed contact-plate *j*, having as many teeth as there are messages marked or provided for on the plate *i'*, and these teeth are so arranged that the spring *j'* bears on one of them when the pointer is set opposite any one of the messages; but the spring *j'* is opposite a space when the pointer is at zero, as shown at Fig. 2. This spring *j'* is fastened to an insulating-block, *j''*, and to it is connected the line-wire *c*.

As a means for holding the pointer *i''* in any of its set positions, the serrated disk *k*, secured to the pointer-shaft, is engaged by the tooth on the end of the flat spring *k'*, which is secured to the end of the pivoted arm *k''*, and this arm is locked so as to hold the spring *k'* in position to act as the retaining spring-pawl of the disk *k*, by the free end of the armature *l*, being under the free end of the arm *k''* when the armature is held back by its spring *l'*.

Projecting from the arm *k''* is an extension, *k''*, provided with a tooth on its end, arranged at the side of the disk *k*, opposite the tooth on the spring *k'*, and with it constitutes a retarding-escapement device for the disk *k* when the armature *l* is drawn away from the arm *k''* by its electro-magnet *l'*, and the spring *i''* is acting on the shaft to bring the pointer back to zero. Instead of this retarding-escapement device acting directly on the motor-spring shaft, its motion may be regulated by means of an independent speed-regulator acting thereon through a train of gear-wheels. One end, *l''*, of the coil of the electro-magnet *l'* is connected to the metallic case *i*, and the other end *l''* is connected to the main line *h*, the current passing from the coil of the magnet through the case *i*, the shaft, and the plate *j* to the

line *c*, through the spring *j'*, when it bears on any of the teeth of the plate *j*.

To provide for a simple call being made from any of the rooms, by causing the call-bell *f'* to be actuated and the corresponding number of the annunciator exposed, as ordinarily, a spring-acting lever, *j*³, is pivoted in the case *i* and closes the circuit between the lines *h* and *c* by contact with the plate *j'*, attached to the back of the insulating-block *j*², which is in metallic connection with the line *c*.

The message-indicator *d* has a cylindrical case, made of suitable insulating material, and a metallic cover or front-plate, *d*³, on which are marked or attached the set of messages corresponding to those on the communicators *a*, &c. A metal disk, *m*, having insulating-spaces formed around its periphery corresponding in number to the number of rooms and divisions in the annunciator *b*, is supported on the insulated bearing *m'*, secured to the under side of the metal cover *d*³. This disk *m* is provided with the handle *d'*, which projects through a slot formed in the side of the case, and to it is fastened the spring *m*², connected to the wire *f*, leading to the part *g* of the battery. Around the interior of the case are fastened the springs *n* *n'* *n*², &c., to which are respectively connected the ends of the line-wires *e* *e'* *e*², &c.; and the free ends of these springs are so formed as to bear on the teeth of the disk *m* when the handle *d'* is in its upward position, and to be opposite the insulating-spaces between the teeth when the handle is pressed down, as shown at Fig. 4. All of the room-circuits are then broken, and any of them may be closed by pressing on a button, *d*². These buttons are secured to springs *d*², attached to the front plate or cover, *d*³, and are provided with pins *d*³, which pass through holes in the plate *d*³, between the teeth of the disk *m* on the springs *n* *n'*, &c., when the buttons are depressed. The front plate, *d*³, is connected to one end, *o*, of the coil of the electro-magnet *o'*, the other end of the coil being joined to the battery *g'* by the wire *g*². The armature *p* of this electro-magnet is pivoted at *p'* to the case, and carries on its upper end the hooked pawl *p*², which catches into the teeth of the ratchet-wheel *q*, secured to the shaft *q'*, having bearings in the center of the case and projecting beyond the cover or plate *d*³, to which projecting end is secured the pointer *r*. A coil-spring, *s*, is attached to the shaft *q'* and the case in such a manner as to be wound up when the pawl *p*² of the armature *p* is caused to act on the ratchet-wheel *q* by the attraction of other end of the armature toward the electro-magnet *o'*, when the current is flowing through its coils, which is when the spring *j'* is in contact with the teeth of the plate *j*. Each action of the pawl *p*² on the ratchet *q* brings the pointer *r* forward successively opposite the messages marked on the plate *d*³, and the ratchet-wheel *q* is retained as set by the pawl *p*² by the retention-pawl *s*.

To permit of all parts of the instrument assuming their normal positions when the handle *d'* is released, a pin, *t*, projecting from the disk *m*, strikes the under side of the retention-pawl *s*, lifting it clear of the teeth of the ratchet *q*, and this pawl in its turn lifts the hooked pawl *p*² clear of the teeth by coming in contact with a prolongation extending above the pawl *s*, thereby entirely freeing the ratchet *q* and allowing the spring *s* to move the pointer *r* back to zero.

Having described the nature of my invention and the manner in which it may be practically carried out, what I claim, and desire to secure by Letters Patent, is—

1. In an electrical communicating system, in combination, an electric circuit comprising one main line from the central station or office to all of the sub-stations or rooms, and individual lines from all of the sub-stations or rooms to the central station or office, communicators constructed to send any of a set of signals or messages included in the individual lines at the sub-stations or rooms, a calling-instrument to show that a signal is ready for transmission, and a message-receiving indicator connected to all of the individual lines and the main line, and mechanism to simultaneously break all the individual lines, thereby cutting out all the communicators, and to complete the circuit of any of the communicators through its individual line and the main line and increasing strength of current on line, substantially as set forth.

2. In an electrical communicating system, in combination, an electrical circuit comprising one main line from the central station or office to all of the sub-stations or rooms, and individual lines from all of the sub-stations or rooms to the central station or office, communicators constructed to send any one of a set of signals or messages included in the individual lines at the sub-stations or rooms, a message-receiving indicator connected to all of the individual lines and the main line, and provided with mechanism to simultaneously break all the individual lines, thereby cutting out all the communicators, and to complete the circuit of any of the communicators through its individual line and the main line, an annunciator in the individual lines, and a battery included in the main line, the current of which is increased to put the communicator and indicator in action, substantially as set forth.

3. In an electrical communicating system, in combination, an electrical circuit comprising one main line from the central station or office to all of the sub-stations or rooms, and individual lines from all of the sub-stations or rooms to the central station or office, communicators constructed to send any of a set of signals or messages included in the individual lines at the sub-stations or rooms, a message-receiving indicator connected to all of the individual lines and the main line, and provided with mechanism to simultaneously

break all the individual lines, thereby cutting out all the communicators, and to complete the circuit of any of the communicators through its individual line, an annunciator in 5 the individual lines, a battery included in the main line, and a call-bell in a line connecting the receiving-indicator and a part of the battery when all the individual lines are closed by the receiving-indicator, substantially as set to forth.

4. In an electrical communicating system, in combination, a series of communicators provided each with a pointer adapted to be set opposite any of a set of messages marked thereon, and so held by means of an electro-magnetic device, a message-indicator provided with a pointer and having messages marked thereon similar to those on the communicators, and an electro-magnetic device adapted to 15 move the pointer opposite any of the messages, separate lines between the communicators and indicator, and including an annunciator, a battery and a main line connecting all the communicators thereto, a line from a part of the battery, and a call-bell therein connected to the indicator, another line connecting the end of the battery to the indicator, so as to include the whole of the battery in the main line, and mechanism, substantially as described, in the 20 indicator, whereby all the communicator-circuits and call-bell circuit are broken and any of the communicators put in circuit with the whole of the battery and indicator, as and for the purposes set forth.

35 5. In an electrical communicating system, a message-receiving indicator comprising the following elements in combination: a series of independent contact-springs, a plate in connection with a line-circuit constructed to make 40 and break contact with the springs simultaneously, push-buttons in connection with another part of the line-circuit corresponding in number to the contact-springs, and arranged to close the respective circuits thereof, an electro-magnetic device in circuit with the push-buttons, and a pointer operated by the electro-magnetic device, substantially as and for the 45 purpose set forth.

6. In an electrical communicating system, a 50 communicator having an escapement-wheel, a spring pawl or tooth carried by a pivoted arm and constituting, with a toothed extension of said arm, a retarding-escapement for the wheel, an electro-magnet and its pivoted armature, 55 said armature so constructed and arranged as to lock the pivoted arm when away from its magnet and hold the spring-pawl in the es-

capement-wheel, thereby causing it to act as a spring retention-pawl, substantially as and for the purposes set forth.

7. In combination, the communicators *a a'* *a²*, &c., constructed to send any of a set of signals, the annunciator *b*, for indicating the room calling, the line-wires *c c' c²*, &c., connecting the communicators to the annunciator, the indicator *d*, constructed to indicate the signal at which any of the communicators may be set, the line-wires *e e' e²*, &c., connecting the annunciator to the indicator, the battery *g g'*, the wire *g'*, connecting the end *g'* of battery to the 70 indicator when receiving a signal, the main line *h*, connecting the other end of the battery to the communicators, the wire *f*, connecting the part *g* of the battery to the indicator, when a call is sent from any of the rooms, 75 and the call-bell *f'*, included in the circuit of wire *f*, substantially as set forth.

8. In combination, the toothed plate *m*, springs *n n' n²*, &c., ratchet-wheel *q*, shaft *q'*, spring *s*, armature *p*, and pawl *p'*, electro-magnet *o*, retention-pawl *s'*, and releasing-pin *t* on the plate *m*, substantially as set forth.

9. In combination, the springs *n n' n²*, &c., attached to the lines *e e' e²*, &c., the toothed plate *m*, the call-bell *f'*, connected by line *f* thereto, the push-buttons *d² d'*, carried by the front plate, *d³*, the electro-magnet *o*, connected to the front plate, *d³*, the battery *g g'*, main line, and the communicators connected to the main line on the lines *e e' e²*, &c., through the lines 90 *c c' c²*, &c., through the annunciator *b*, substantially as set forth.

10. In combination, the serrated disk *k*, spring *i²*, arm and toothed extension *k² k³*, spring-pawl *k'*, and armature *z*, substantially 95 as set forth.

11. In a message-indicator, in combination, a spring-acting pointer and ratchet-wheel, a feeding-pawl actuated by an electro-magnetic device, a retention-pawl for holding the pointer 100 and ratchet-wheel stationary, and a contact device for making and breaking a number of electric circuits, and provided with a pin projecting from its face for moving the feeding and retention pawls clear of the ratchet-wheel, 105 substantially as set forth.

In testimony whereof I have hereunto set my hand, at New York, county and State of New York, this 13th day of August, A. D., 1885.

ALFRED G. HOLCOMBE.
In presence of—

WM. G. STARRETT,
ALFRED SHEDLOCK.
